UNITED STATES PATENT OFFICE.

RICHARD ARMOUR, OF LOS ANGELES, CALIFORNIA.

DRILL JAR AND THE METHOD OF MAKING SAME.

Application filed October 4, 1923. Serial No. 666,464.

To all whom it may concern:

Be it known that I, RICHARD ARMOUR, a citizen of the United States, residing at Los Angeles, in the county of Los Angeles and State of California, have invented new and useful Improvements in Drill Jars and the Methods of Making Same, of which the following is a specification.

This invention relates to an instrument known as a drill jar used as a member in a string of drilling or fishing tools in the cable system employed in drilling wells, and particularly pertains to the method of making the jar.

It is well known that drill jars consist of two reins, an upper and a lower, disposed parallel to each other in right angle planes and interconnected. The upper rein comprises essentially three sections, namely, a head or cap constituting an end portion of the rein, a middle section having side members and a slot therebetween, and a bottom section which impacts against a seat in the lower rein momentarily after the drilling tool strikes the bottom of the well in drilling action.

The lower or bottom rein is substantially of the same structure as the upper rein, except that the lower end of the lower rein is adapted to be secured to the drilling tool, whereas the head of the upper rein is somewhat differently adapted to be indirectly connected to the cable.

In making a drill jar according to previous practice the head portion and the slotted portion of a rein have been manufactured separately in finished form in order to permit interconnection of one rein with the other. The slotted portion of the rein then forms a fork having the side members of the slot as prongs, and the head portion being formed at one end on a line to abut against and joined to the ends of the prongs and extending across the end of the slot, after the fork of the lower rein has been inserted in the fork of the upper rein, and properly adjusted in a plane at right angles to the plane of the upper rein. The heads of the reins are then welded to the forks. The weld joint thus formed extends at right angles to the stress thereon occurring when the cable system is suddenly raised causing the top of the slot of the lower rein to impact against the lower end of the slot of the upper rein. This sudden stress or live load is necessitated by the fact that the drilling tool is usually

partly embedded in the rock when striking the same in downward motion, requiring therefore a sudden jerk of the cable system to loosen it from the rock, this jerk placing the reins of the jar in tension and placing a strain on the one-plane weld at right angles to it. The result of making such a weld has frequently resulted during drilling in knocking the head off of the upper rein, by which action the drilling tool is lost and has to be fished out, which is an expensive, tedious, difficult and sometimes impossible operation, and in the latter instance the well must sometimes be abandoned.

It is therefore an object of this invention to provide an improved drill jar by making the reins in such manner that they cannot be broken so readily.

Another object of this invention is to provide a method for connecting the two reins of my improved drill jar.

Other objects may be inferred from reading the following specification.

My invention will be more readily understood by reference to the drawings, in which—

Figure 1 is a side elevation of an upper rein.

Figure 2 is a side elevation of a partially finished lower rein.

Figure 3 is a perspective view showing a step in the process of interconnecting the upper and lower reins.

Figure 4 is a perspective view showing the reins in normal adjustment but with the lower rein unfinished.

Figure 5 is a perspective view of the finished jar.

More particularly, Figure 1 shows an upper rein 8 consisting of a head portion 9, a bottom portion 10, and a middle portion 11 having side members 13 and 14 as sides of a slot 15. The sides 13 and 14 are temporarily spread apart, which may be done by bowing outwardly opposing sections of the sides 11 and 14, as shown, respectively, at 17 and 18; this operation being effected for the purpose of providing space for the proper adjustment of the lower rein, as will appear more clearly hereinafter.

Figure 2 shows the lower rein 19 as consisting of an unfinished bottom end portion 20, an upper end portion 21, a middle portion 22 having side members 23 and 24, enclosing a slot 25, the end portion 21 and the middle portion 22 being in finished form.

The rein 19 is then cut in a line extending from a point 29 near the bottom of the slot 25 to a point 30 on the outer surface of the lower end portion 20, the line 27 being directed at first in a direction longitudinally of the rein, and then curved to form scarfed interlocking members 32 and 33. By this severance the side member 23 is severed from the lower end 20 of the rein and may then be pulled outwardly, preferably at a high temperature, in the form 35 shown in dotted lines, leaving an opening 36 between it and the scarfed portion 33.

The side member 14 of the rein 8 may then be passed through the opening 36 at its bowed portion 18 and passed under the outwardly pulled severed member 35 of rein 19, the outwardly bowed section 17 of the side member 11 of rein 8 being passed over the outwardly pulled side severed member 35, the rein 8 being held in a position substantially transverse to the rein 19, as shown in Figure 3.

After the reins are properly positioned with respect to each other, the head end of the rein 8 may be turned in a clockwise direction until the rein 8 is nearly parallel to the rein 9. The rein 8 may then be turned over through substantially ninety degrees, when the end section 21 of the rein 19 will fit into the upper end of the slot 15, and the lower end 10 of the rein 8 will fit into the lower end of the slot 25; the reins then being parallel to each other in right angle planes, as shown in Figure 4.

After properly adjusting the reins 8 and 19 with respect to each other, the outwardly extending arm 35 may be placed back in its normal position so that the scarfs 27 and 32 interlock.

The rein 19 may then be welded along the line of severance 27, after or before which process the bowed-out side sections 17 and 18 of the rein 8 may be straightened to normal position.

It will be perceived that by employing

my drill jar stress is not placed on the weld when the reins are in tension but is placed on integral parts of the reins.

The lower end portion of the rein 19 may then be finished according to the usual methods to the form shown in Figure 5.

By thus forming the reins, only one of the reins is welded, and the welded rein is formed of one piece of metal of the same character throughout which facilitates the formation of a proper weld at the joint, as a more perfect fusion may be effected than where two separate pieces of metal having different carbon elements are joined, as is now the common practice. This, with the interlocking formation of the parts of the joint and the general extension of the joint in the direction of pulling or pushing strains, insure against separation of the joint due to working strains on the jars.

I claim—

1. In a drill jar, a rein having a pair of side members and joined together at one side thereof and adapted to be separated at their other ends, the separable end portions of the side members being scarfed to provide an interlocking joint, and said scarfed end portions being welded together along the interlocking joint.

2. The method of making a pair of jar links which consists in initially forming a pair of separate links with the side members of each link connected together at their ends, then severing the stock at the ends of the side members of one of the links with the severance extending diagrammatically into the side of the stock and then returning at an angle and leading to the space between the sides of the link members, thus freeing one of the side members of a link, which is then bent outwardly and passed through the other link and thereafter straightened and joined at the line of severance by welding.

RICHARD ARMOUR.
